Primary Examiner — Vy N Koenig

(57) **CLAIM**

The ornamental design for a welding mask, as shown and described.

DESCRIPTION

FIG. 1 is a front perspective view of a welding mask showing our new design;

FIG. 2 is a front elevation view of the welding mask of FIG. 1;

FIG. 3 is a rear elevation view of the welding mask of FIG. 1;

FIG. 4 is a right side view of the welding mask of FIG. 1; FIG. 5 is a left side view of the welding mask of FIG. 1; FIG. 6 is a top view of the welding mask of FIG. 1; and, FIG. 7 is a bottom view of the welding mask of FIG. 1. The broken lines shown in the drawings represent portions of the welding mask that form no part of the claimed design.

1 Claim, 7 Drawing Sheets
